Primary Examiner — John R Yeh(74) *Attorney, Agent, or Firm* — Reyes Law Services;
 Hector M. Reyes Rivera(57) **CLAIM**

The ornamental design for a paint scraper, as shown and described.

DESCRIPTION

FIG. 1 is a perspective view of the paint scraper showing my new design;

FIG. 2 is a top view thereof;

FIG. 3 is a bottom view thereof;

FIG. 4 is a left-side view thereof;

FIG. 5 is a right-side view thereof;

FIG. 6 is a rear view thereof; and,

FIG. 7 is a front view thereof.

The broken lines in the drawings are for illustrative purposes only and form no part of the claimed design.
